Primary Examiner—Theodore M. Shooman*Assistant Examiner*—Lucy Lieberman*Attorney, Agent, or Firm*—Julie Blackburn[57] **CLAIM**

The ornamental design for a combined bottle and closures with nested vial, as shown and described.

DESCRIPTION

FIG. 1 is a front elevation of a combined bottle and closures with nested vial showing my new design;

FIG. 2 is a top plan view thereof;

FIG. 3 is a perspective view of the bottle with nested vial shown without the closures for clarity of illustration;

FIG. 4 is a top plan view of FIG. 3;

FIG. 5 is a front elevation of FIG. 3;

FIG. 6 is a rear elevation of FIG. 3;

FIG. 7 is a left side elevation of FIG. 3;

FIG. 8 is a right side elevation of FIG. 3;

FIG. 9 is a bottom plan view of FIG. 3;

FIG. 10 is a perspective view of the bottle shown without the closures and vial for clarity of illustration;

FIG. 11 is a top plan view of FIG. 10;

FIG. 12 is a front elevation of FIG. 10; and,

FIG. 13 is a left side elevation of FIG. 10.
